BOWLING BALL RETURN RACK OR THE LIKE

Robert I. Anderson, Muskegon, Mich., assignor to Brunswick Corporation, Chicago, Ill., a corporation of Delaware

Filed June 27, 1960, Ser. No. 61,111

Term of patent 14 years

(Cl. D34—5)

Fig. 1 is a top plan view of a bowling ball return rack or the like showing my new design;

Fig. 2 is a side elevational view thereof; and

Fig. 3 is an end elevational view thereof.

The side opposite that shown is substantially identical to that shown.

I claim:

The ornamental design for a bowling ball return rack or the like, as shown and described.
